METHOD OF CONSTRUCTING MONOLITHIC CANALIZED STRUCTURES

Jean Pierre Louis Mourraillé, Paris, France,
assignor to Sté dite: SATUJO, Sté An^{me} de
Construction de Tuyaux sans Joints, Système
Cravetto Breveté S. G. D. G., Paris, France

Application July 1, 1933; Serial No. 678,711
In France October 28, 1932

10 Claims. (Cl. 25—154)

This invention relates to a method of constructing monolithic canalized structures, and more particularly refers to the construction of canalized structures in cement, reinforced or otherwise, mixed directly on the spot, without joints.

Monolithic pipes made of cement or like materials by employing moulds formed by an elastic core, for example a pipe made from a flexible material such as canvas or rubberized fabric, inflated and maintained under pressure by means of an appropriate fluid, are not in a broad sense new. Various means have also been suggested for the removal of the aforesaid core, as each pipe section is completed.

However, the construction of such pipes in cement mixed directly on the spot, without joints, could not be successfully carried out with the methods heretofore known, as none of them permits the removal of the core in such a way as to leave undamaged the internal surface of the pipe and the core itself.

This invention has for its object to provide a method enabling an easy removal of the aforesaid core in constructions of the type mentioned, said method being characterized in that it consists in maintaining the core under pressure during the time when said core is withdrawn.

During the operation of the core (mould pipe) removal, it is preferable to maintain said core under a pressure almost equivalent to the pressure maintained in the said core during the pouring of the cement.

Another feature of the method is that the flexible core is removed by causing the mould pipe to be gradually turned within itself so as to insure the flow of the fluid used for the inflation thereof, while the pressure within the core is maintained.

In order that the invention may more readily be understood and carried into practice embodiments thereof will now be described, solely by way of example, with reference to the accompanying drawings, in which:

Fig. 1 is a view in longitudinal section of a form of device whereby the method according to the invention can be carried into practice;

Fig. 2 is a front view of the distributing tray; Fig. 3 is a sectional view taken on the line III—III of Fig. 2;

Fig. 4 is a view in vertical section showing another form of device, also adapted to carry the invention into practice; and

Fig. 5 is a plan view corresponding to Fig. 4.

The process according to the invention is an improvement over previous methods, which consist in utilizing for the construction of canalized structures without joints in cement, reinforced or not, a mould pipe made from a flexible material

or substance, for instance, canvas or rubberized fabric, inflated with an appropriate fluid and maintained under pressure while the cement is mixed and poured over it.

With the heretofore known process, it has been found impossible to withdraw the mould pipe when each canalized section is completed, as this withdrawal causes damage to the mould pipe itself and to the inner surface of the canalized structure, in some cases even diminishing the internal resistance of said structure.

According to the invention, the withdrawal is effected in turning the mould pipe inside out while still under pressure, as will be presently explained.

The mould pipe during the whole time of the withdrawal is maintained under a pressure almost equivalent to the pressure used while the cement is being poured. This procedure permits of obtaining a canalized structure having a uniform section throughout its length and also prevents damage to the mould pipe while it is being withdrawn.

In the process according to the invention, as illustrated in Figs. 1 to 3, I utilize for the construction of canalized structures without joints, a collapsible core 1, that is to say, a pipe made from a flexible substance or material, such as, for instance, canvas or rubberized fabric, of a length and diameter corresponding to the dimensions of the canalized structure 2 to be produced.

The pipe 1 is closed at one end, by means of an appropriate fastening or bushing 3; a cable 4 going across said closed end. The fastening 3 must be such that the pipe is perfectly watertight, and on the other hand, cable 4 must be fixed so that it will not slip.

The length of cable 4 should preferably be at least twice the length of pipe 1; the portions of said cable 4 remaining respectively inside and outside pipe 1 being approximately of the same length.

At its open end, pipe 1 is equipped with an apparatus or device shown in detail in Figs. 2 and 3. This device comprises two flanged bushings 5 and 6, which are to be fixed respectively to the mould pipe 1 and to a supply conduit containing a fluid under pressure, coming either from a tank or a pump, or any other suitable source.

The two bushings 5 and 6 are coupled to each other by means of bolts or any other suitable means 7, a distributing tray 8 being interposed therebetween. Said tray is provided with two series of valves 9 and 10, opening in opposite directions (see Fig. 3) and consequently referred to as inlet valves and exhaust valves.

The valves 9 and 10 are equal in number (four in example shown) and are evenly distributed on the tray.

The springs 11 of the exhaust valves 10 are so arranged that they can only open when the pres-

sure in the flexible pipe 1 is above a predetermined maximum, controlled by a manometer 12, fitted on bushing 5.

Cable 4 extends through the center of the distributing tray 8 which is correspondingly provided with a suitable absolutely water-tight device 13 embracing said cable.

When a canalized structure without joints is to be constructed, a flexible pipe 1 of an appropriate length is placed upon a bed of cement, and bushing 6 is joined to the pipe supplying the fluid under pressure. Under the action of said fluid, inlet valves 9 open and the fluid penetrates within the flexible pipe 1. When the pressure in the flexible pipe has reached the predetermined value indicated by the manometer 12, the supply of fluid is turned off or else bushing 6 is detached from the supply pipe. Inlet valves 9 are then maintained on their respective seats, on one side by their spring 14 and on the other side by the fluid contained in the mould pipe 1. On the other hand, the pressure within the mould pipe remains unchanged, said pipe being waterproof.

Cement is then poured in the usual manner around the flexible pipe 1.

Unless it has already been done, bushing 6 is then disconnected from the supply pipe of the fluid under pressure, preparatory to the removal of the mould pipe. Cable 4 is then pulled outwardly through tray 8, by means of a handle 15. This operation has for its object to increase the pressure inside the flexible pipe 1 whereby exhaust valves 10 will immediately open; consequently, the fluid under pressure contained in the flexible pipe 1 is forced out, while at the same time the flexible pipe is turned inside out, as shown in Fig. 1.

The pull on cable 4 is maintained until the end of the fastening of the pipe 1 reaches against the device 13. At this stage, bushing 5 is disconnected so as to remove pipe 1 from its housing. It is necessary to replace the fluid retaining apparatus described by a suitable coupling, so as to let the water contained in pipe 1 come out slowly as said pipe is turned inside out.

Another device which makes it possible to insure the complete withdrawal of pipe 1, in just as good a condition as the apparatus previously described, is shown in Figs. 4 and 5, this second device having the advantage of greater simplicity.

In this case, for creating pressure within pipe 1, it is necessary to use a tank 16 resting upon the ground by means of supports 17, the height of these being such that the pressure inside pipe 1, as it will be seen later, will be sufficient to maintain the latter fully expanded when the cement is poured.

The tank 16, which can be of any suitable form, is provided with inclined tubes 18, extending through its bottom and supported by means of packing 19.

The upper ends of tubes 18 are cut at a slant and are placed horizontally in a common plane. The tank has, besides, an overflow outlet 20 at the same level as the horizontal plane delimiting the upper ends of tubes 18. The overflow outlet 20 is equipped with a drain 21.

The device is completed by a shaft 22 carried by the tank 16 and provided with a loose roller 23.

The method of manipulating this device is as follows:

The trench 24 in which the canalized structure is to be located having been prepared, a lining 25 is poured at the base of this trench, and upon

be used as moulds for the construction of the canalized structure.

As shown, the closed end of each pipe 1 is inserted within the front end of the stump of canalized structure previously constructed, the free end of the said pipe being inserted over the corresponding tube 18 with the assistance of suitable means.

The various pipes 1 being connected to the corresponding tubes 18 are filled with a fluid, 10 water for example, until they attain the required pressure.

This being done, tank 16 is also filled with the fluid, the fluid level in the said tank reaching only the upper ends of tubes 18.

By virtue of this arrangement an equal pressure obtains and is maintained within the various pipes 1.

The cement for the construction of the canalized structure is then poured, as in the previous 20 case.

For the withdrawal of the cores, it is only necessary to pull on cables 4, which cause the cores to be turned inside out.

As each pipe is thus turned, the water it contains is discharged into tank 16 and thence immediately through outlet 20.

No matter what the position of pipes 1 is, the level of the water in the tank 16 remains the same, and it follows that also the pressure in the 30 pipes 1 remains uniform.

The roller 23 has for its object to maintain the proper alignment of cables 4 and to facilitate their operation while the pull is applied thereto.

It is, of course, possible to use a second tank 35 combined with tank 16, adapted to collect the water discharged from the latter as each pipe 1 is turned inside out. In this manner the water used for putting the pipes under pressure can be saved, this being particular interesting 40 when working in localities where water is scarce.

It also means a saving in the cost of constructing the canalized structure.

By the process according to the invention, it is possible to effect a quick withdrawal of the 45 flexible core 1 without the canalized structure being damaged internally in any manner. It is, therefore, possible to produce tubular conduits of an even section.

The feature of withdrawing the flexible core 1 50 whilst still under pressure prevents the said core from sagging and forming within the conduit an obstruction preventing it from yielding in the inside out turning thereof.

Although the invention has been described in 55 connection with single pipe structures, it can obviously be applied for the construction of canalized structures with numerous channels. In such case, the required number of flexible pipes are placed near one another and maintained 60 suitably apart by appropriate means, sluices or others.

For the construction of a canalized structure of reinforced cement the procedure is as explained above, the conduit to be covered with cement 65 being made of a metallic trellis placed around the mould pipe.

It is obvious that the invention is in nowise limited to the embodiments which have been more especially described by way of example, but that it extends to all possible modifications coming, fairly, within the scope of the appended claims.

I claim:

1. In a method of constructing a canalized 75

75 said lining are placed the pipes 1, which are to

- structure whereby a self-setting plastic material is poured about a hollow, flexible core inflated by fluid pressure, and said core is subsequently withdrawn after said material has reached a 5 suitable degree of consistency, the step which consists in pulling the inner end of said core throughout the length thereof so as to cause said core to be turned inside out and thus to become gradually disengaged from the inner surface of 10 said structure, and maintaining said core under a pressure sufficient to maintain the inflation of its unturned portion, while its withdrawal takes place.
2. In a method of constructing a canalized structure whereby a self-setting plastic material is poured about a hollow, flexible core inflated by fluid pressure, and said core is subsequently withdrawn after said material has reached a suitable degree of consistency, the step which 15 consists in pulling the inner end of said core throughout the length thereof so as to cause said core to be turned inside out and thus to become gradually disengaged from the inner surface of said structure, and maintaining said core under 20 a substantially uniform pressure sufficient to maintain the inflation of its unturned portion, while its withdrawal takes place.
3. In a method of constructing a canalized structure whereby a self-setting plastic material is poured about a hollow, flexible core inflated by fluid pressure, and said core is subsequently withdrawn after said material has reached a suitable degree of consistency, the step which 25 consists in pulling the inner end of said core throughout the length thereof so as to cause said core to be turned inside out and thus to become gradually disengaged from the inner surface of said structure, and maintaining said core under 30 a substantially uniform pressure while its withdrawal takes place, said pressure being substantially equivalent to the fluid pressure employed to maintain said core in its inflated condition during 35 the pouring of said plastic material.
4. The method of constructing a canalized structure, which consists in pouring a self-setting plastic material about a hollow, flexible core inflated by fluid pressure, and after said material has reached a suitable degree of consistency, withdrawing the core by pulling its inner end 40 throughout the length thereof so as to cause said core to be turned inside out and thus to become gradually disengaged from the inner surface of said structure, while a pressure sufficient to maintain the inflation of its unturned portion, is 45 maintained within said core.
5. The method of constructing a canalized structure, which consists in pouring a self-setting plastic material about a hollow, flexible core inflated by fluid pressure, and after said material 50 has reached a suitable degree of consistency, withdrawing the core by pulling its inner end throughout the length thereof so as to cause said core to be turned inside out and thus to become gradually disengaged from the inner surface of said structure, while a substantially uniform pressure sufficient to maintain the inflation of its unturned portion, is maintained within said core.
6. The method of constructing a canalized structure, which consists in pouring a self-setting plastic material about a hollow, flexible core inflated by fluid pressure, and after said material 55 has reached a suitable degree of consistency, withdrawing the core by pulling its inner end throughout the length thereof so as to cause said core to be turned inside out and thus to become gradually disengaged from the inner surface of said structure, while the water therein contained is gradually ejected therefrom, and maintaining said water under a predetermined constant head, during both the pouring and the core reversing operation.
- core to be turned inside out and thus to become gradually disengaged from the inner surface of said structure, while a substantially uniform pressure is maintained within said core, said pressure being practically equivalent to the pressure employed to maintain said core in its inflated condition during the pouring of the plastic material.
7. The method of constructing a canalized structure, which consists in pouring a self-setting plastic material about a hollow, flexible core filled with a fluid under pressure, maintaining the same in an inflated condition, and, after said material has reached a suitable degree of consistency, withdrawing the core by pulling its inner end throughout the length thereof, so as to cause said core to be turned inside out and thus to become gradually disengaged from the inner surface of said structure, while the fluid therein contained is gradually ejected therefrom, and applying an action antagonistic to the outflow of said fluid at least to the extent of maintaining the inflation of the unturned portion of the core.
8. The method of constructing a canalized structure, which consists in pouring a self-setting plastic material about a hollow, flexible core filled with a fluid under pressure, maintaining the same in an inflated condition, and, after said material has reached a suitable degree of consistency, withdrawing the core by pulling its inner end throughout the length thereof, so as to cause said core to be turned inside out and thus to become gradually disengaged from the inner surface of said structure, while the fluid therein contained is gradually ejected therefrom, and applying an action antagonistic to the outflow of said fluid so as to maintain the non-ejected portion thereof under a substantially uniform pressure at least sufficient to maintain inflated the unturned portion of the core.
9. The method of constructing a canalized structure, which consists in pouring a self-setting plastic material about a hollow, flexible core filled with a fluid under pressure, maintaining the same in an inflated condition, and, after said material has reached a suitable degree of consistency, withdrawing the core by pulling its inner end throughout the length thereof, so as to cause said core to be turned inside out and thus to become gradually disengaged from the inner surface of said structure, while the fluid therein contained is gradually ejected therefrom, and applying an action antagonistic to the outflow of said fluid so as to maintain the non-ejected portion thereof under a pressure substantially equivalent to the pressure used to maintain said core in an inflated condition, while the plastic material is being poured.
10. The method of constructing a canalized structure, which consists in pouring a self-setting plastic material about a hollow, flexible core filled with water under pressure, maintaining the same in an inflated condition, and, after said material has reached a suitable degree of consistency, withdrawing the core by pulling its inner end throughout the length thereof, so as to cause said core to be turned inside out and thus to become gradually disengaged from the inner surface of said structure, while the water therein contained is gradually ejected therefrom, and maintaining said water under a predetermined constant head, during both the pouring and the core reversing operation.
